Application August 21, 1945, Serial No. 611,778

4 Claims. (Cl. 46—43)

This invention relates to toys and more particularly to a characteristic toy or amusement device in which marbles or spherical elements are placed in a container and released automatically in succession from the container and transferred to a receiver in a manner through ingenious provision which makes the operation of the device amusing and interesting.

An object of the invention is to simplify the construction and arrange the same for the automatic operation thereof with positive and uninterrupted action.

Another object is to produce a device of this character which, although operative automatically with positive action as above described, yet, to one who has not previously observed the operation of the device, its operativeness is seemingly impossible and thus its actual operation is consequently of interest and amusement.

Other objects and advantages to be attained will hereinafter more fully appear in the following description.

An illustration of a practical adaptation of the invention is illustrated in the accompanying drawings, in which:

Figure 1 is a side elevational and partial sectional view of the device;

Figure 2 is a top plan view;

Figure 3 is a vertical longitudinal section taken on or about the line 3—3 of Figure 2;

Figure 4 is an end view of the device; and

Figure 5 is a detail view of the trigger element or release control member for the spherical elements in the container.

Referring now to the drawings, the numeral 6 designates, generally, the supporting frame of the device. As shown, the frame comprises four rectangularly arranged uprights or posts 7 secured at their lower ends on a base plate 8.

Mounted on the upper ends of the frame uprights or posts 7 is an inclined container or hopper of elongated form and substantially V-shaped in cross section. This hopper 9 may or may not be closed at its high end but it is closed at its lower end by a transverse wall or abutment member 10.

Contiguous to the end wall or abutment 10, the lower portions of the downwardly convergent side walls of the container or hopper are cutaway, as at 11, to provide an opening of the size to permit free passage therethrough of the respective spherical elements or marbles 12 one at a time from the container or hopper 9.

An elongated pivotally mounted and tiltable transfer element 13 is supportedly mounted be-

tween the forward pair of uprights or posts 7 which support the lower end portion of the container or hopper 9, said element 13 being swingable about a pivotal axis 14 which is located substantially midway between its opposite ends, and its inner end portion 15 being weighted to overbalance its forward end portion so that the element will normally assume the inclined position shown in Figure 1. The outer or upper end portion of the transfer element 13 is provided with a substantially rectangular notched recess or pocket 16 which is open at the end of the element 13 and also the upper side thereof.

The normal position of the transfer element 13, when unloaded, is that indicated in Figure 1, but when said element 13 becomes loaded by the reception of one of the spherical elements 12 in said pocket portion 16, the element is then overweighted at its outer end, whereupon said transfer element tilts to the forwardly and downwardly inclined position shown in Figure 3 and the spherical element 12 in the pocket 16 rolls from the pocket and drops into a receiver or chute 17 which is elongated and rearwardly and downwardly inclined, as indicated in Figure 1.

The forward end of the receiver or chute 17, as shown, is closed by a transverse wall or abutment member 18. The lower rear end of the receiver or chute 17 may or may not be closed, as desired. However, as shown, a stop element 19, in the form of an elongated rectangular bar, is pivoted at one end, as at 20, to one of the uprights or posts 7 which support the higher rear end portion of the container or hopper 9. The free end portion of this stop element 19 is swingable into and out of closing relation across the rear end portion of the receiver or chute 17 and it rests on a ledge 21 provided at the end of the bottom of the receiver or chute. In this connection, it is here noted that the forward portion of the receiver or chute 17 is of considerable width but the major longitudinal portion of the receiver or chute is narrower and elongated, this narrow and elongated portion being disposed and supported on the outer sides of the adjacent uprights or posts 7 near the lower ends thereof.

Working in the forward end portion of the container or hopper 9, in proximity to the end wall or abutment member 10 thereof, is the upper portion 22 of a trigger element or device 23 for controlling the delivery of the spherical elements 12 from the container or hopper. This trigger element or controlling member comprises a narrow elongated stem portion 24 which is pivotally attached, as at 25, to the transfer element 13 at a

point rearwardly from its pivotal axis 14. As shown, the element 13 is of an elongated rectangular form and it is provided with a longitudinal slot 26 therein, in which slot the end portion of the stem or shank 24 of the member 23 is inserted.

The outer or upper end portion of said element 23 is of a peculiar polygonal form, that is to say, its extreme end portion is of a definite width and substantially rectangular and its next adjacent inner portion is widened somewhat, as at 27, to provide shoulders 28 at opposite sides thereof. The narrower part of the end portion 22 of the element 23 works freely slidably within the cut-away portion 11 of the container or hopper 9 and said shouldered portions 28 afford stops to prevent unlimited outward endwise movement of said element 23 by the possible engagement of said shouldered portions 28 with the adjacent edge portions of the opening 11.

An opening 29, of a diameter large enough to permit free passage of the respective spherical elements 12 therethrough, is provided in the outer end portion of said head 22 of the trigger element or controlling member 23. In certain positions of the trigger element or controlling member 23 during the operation of the machine, this opening 29 is positioned so as to receive a ball from the container or hopper 9, and at other times during the operation of the machine the solid portion of the part 22 just above the opening 29 or the solid portion of the part 27 just below the opening is in a position to arrest the other marbles or spherical elements 12 within the container or hopper 9.

Pivotedly mounted, as at 30, on the end wall or abutment member 10 of the container or hopper 9, is a gravitating stop dog 31 which is normally inclined inwardly and downwardly in the container or hopper with its free end portion in position to arrest the outermost marble or sphere 12 in the row thereof which is located on the bottom of the container or hopper. This gravitating stop dog 31 overhangs the end portion 22 of the trigger element or controlling member 23 and it is lifted from engagement with the marble or sphere 12 in the container hopper 9 upon upward movement of the element 23, and when the element 23 moves downwardly said stop dog 31 swings downwardly therewith into normal marble or sphere arresting position.

The normal position of the operating parts of the device is indicated in Figure 1 and in said illustration the device has not yet been operated.

To start operation of the device, the forward portion of the pivotal transfer element 13 is depressed by the finger of the operator and about the time the element 13 is in a position substantially in the angular relation shown by dotted lines in Figure 3 the element 23 is lifted sufficiently for the opening 29 in the upper end portion thereof to receive the endmost marble or sphere in the container or hopper 9, the row of elements 12 rolling by gravity down the inclined bottom of the container or hopper and pushing the endmost element 12 against the lower portion of the end partition or abutment member 10. At this time the upper end of the element 23 has lifted the stop dog 31 to the full line position shown in Figure 3 so that its free end portion is at a substantial distance above the next adjacent marble or sphere 12. In this connection, it is here noted that, for a positive control and determination of the movement of the element 13 in starting operation of the device, said element 13 may be depressed to the full line lowered position

shown in Figure 3, the downward movement of the element 13 being arrested by the shoulder portions 28 on the head part 27 of the element 23 coming in engagement with the opposed edge portions of the opening 11.

During the continuation of the downward movement of the element 13 from the dotted line position to the full line position shown, said element 23 moves a slight distance upwardly and accordingly lifting the marble or sphere 12 which has entered the opening 29 and during all of this time the marble or sphere is resting against the end wall or abutment member 10. Then, the element 13 is moved by the operator so that the forward end portion is in its normal position as shown in Figure 1 and simultaneously as said element 13 reaches this normal position or to a position closely approximating its normal position the trigger element 23 has been lowered carrying therewith the marble or sphere which has entered the opening 29 of said element to a position below the lower edge of the end wall or abutment member 10, whereupon the marble or sphere drops from the opening 29 and falls into the pocket 16 in the end of the transfer element 13. Upon this happening the marble or sphere 12 that has dropped into the pocket 16 overbalances the outer end portion of the element 13 and said element 13 moves to the full line position shown in Figure 3 and the marble or sphere rolls from the pocket 16 and falls into the outer end portion of the chute 17. During this operation of the device under the weighted influence of the marble or sphere 12 the trigger element 23 has again been lifted to receive in its opening 29 the next adjacent marble or sphere in the container or hopper 9 and the stop dog 31 has, of course, been lifted out of its effective stop position. After the transfer element 13 has been released by the operator as just above described in the starting of the device, operation of the device continues successively and continuously as long as there is a marble or sphere 12 remaining in the container or hopper, the operation then being automatic.

As the marbles or spheres are transferred to the chute 17 they remain as collected therein by provision of the latch bar 19 which is placed across the lower rear end of the chute, or, if desired, the element 19 may be moved out of stop position and the marbles or spheres allowed to roll out of the chute 17 into some suitable receptacle provided therefor adjacent the end of the chute or they may be disposed of in any other desired manner.

From the foregoing it is apparent that a novel amusement device is produced of a simple and amusing character, the operation of which is all the more interesting because of the apparent inoperability of the same to one who has not observed its operation but becomes impressed and causes the device to operate again and again after having once observed the operation of the same.

The illustration in the drawings is but one practical exemplification of the invention. Therefore, considerable modification of the device is contemplated within the purview of the invention as defined by the appended claims and the invention is not limited to the specific construction and arrangement shown.

Having thus described the invention, what is claimed is:

1. A toy of the class described, comprising an elevated container for a plurality of spherical elements, said container having a discharge opening through which the spherical elements are mov-

able out of the container successively and by the influence of gravity, a receiver for the spherical element located in a plane below said container, a transfer element pivotally mounted between said container and said receiver, said transfer element being self-balanced to assume a normal position with a pocket portion thereof located in position to receive a spherical element from said container and upon reception of the spherical element becomes overbalanced adjacent the pocket portion so as to move tiltably to bring the pocket portion in proximity to said receiver whereby the spherical element drops from said pocket portion of the transfer element into said receiver, and a trigger-like controlling element connected operatively to said transfer element and operating effectively in the discharge opening of the container so as to receive the spherical elements successively and deliver them one at a time and intermittently to the pocket portion of the transfer element as the latter returns successively and automatically to its normal position after a previous starting movement of the transfer element to a position approximately that of its final delivery position relative to said receiver.

2. A toy of the class described, comprising an elevated, inclined container for a plurality of spherical elements, said container having a discharge opening in its bottom and adjacent its lower end, through which opening the spherical elements are movable out of the container successively and by the influence of gravity, a receiver for the spherical elements located in a plane below said container, a transfer element pivotally mounted between said container and said receiver, said transfer element being self-balanced to assume a nearly vertical but inclined substantially upright normal position and having an open-ended pocket in its upper end portion and in a position to receive a spherical element from said container, and upon reception of the spherical element said transfer element becomes overbalanced at the side of its pivotal axis adjacent the pocket so as to move tiltably with the pocket forwardly and downwardly disposed to thereby bring the pocket in proximity to said receiver whereby the spherical element drops from the pocket into said receiver, and an elongated trigger-like controlling element having a stem portion connected at its lower end pivotally to said transfer element, said trigger element moving upwardly as the forward portion of the transfer element rocks downwardly, the trigger-like controlling element having an enlarged upper end portion provided with an opening to receive and transfer a spherical element from the container, said enlarged portion operating effectively in the discharge opening of the con-

tainer so as to afford an abutment for the spherical elements in the lowered position of the controlling element but said opening receiving the spherical elements successively in a raised position of said controlling element and in a subsequent lowered position of the element said opening of the element delivers the spherical elements one at a time and intermittently to the pocket of the transfer element as said latter element returns successively and automatically to its normal position after a previous starting movement of the transfer element to a position approximately that of its final delivery position relative to said receiver, the operation of the device thus continuing automatically until the last spherical element is discharged from the container.

3. A toy in the combination and arrangement of parts as set forth in claim 2, wherein a gravitating stop element is movably mounted on the lower end portion of the container in cooperative relation to said trigger-like controlling element whereby to be lifted by said controlling element upon the upward movement of the latter, said stop element in its lowered position engaging the spherical element in the container next adjacent said controlling element and thereby releasably retaining the other spherical elements behind said engaged spherical element in the container, said stop element returning of itself to its normal effective stop position upon downward movement of said controlling element.

4. A toy of the class described, comprising a container for a plurality of spherical elements and having an outlet through which said spherical elements are discharged successively one at a time and moving by gravity to the outlet, a receiver located below said container, a transfer element mounted for operative movement back and forth between said container and said receptacle, said transfer element being arranged and adapted for self-return to a normal sphere-receiving position relative to said receptacle after each sphere-transfer operation, controlling means carried and operated by said transfer element with a part of the controlling means operating intermittently in the outlet of said container for successively and intermittently delivering the spherical elements one at a time from said receptacle onto said transfer element in the normal sphere-receiving position of the latter, the loaded transfer element thereby moving to deliver its carried sphere into said receiver and then returning to its normal sphere-receiving position, and the operation of the device thus continuing automatically until the last spherical element is removed from the container.

RUSSELL T. WALKER.
